COOPERATING CARD ENVELOPE AND A
CARD HOLDER WITH DETENT RE-
TAINING MEANSCarl Lomholt, Bogota, N. J., assignor to Federal
Telephone and Radio Corporation, New York,
N. Y., a corporation of Delaware

Application June 18, 1945, Serial No. 600,039

10 Claims. (Cl. 40—10)

1

This invention relates to designation strip structures of the type as used extensively in conjunction with the operation of telephone switch boards, signal panels and the like.

The designation strips of the type to which the invention relates are employed as a means for identifying signal lamps or jacks which are mounted in horizontal rows in the instance of a telephone switch board and as is well understood, require periodic alteration of the designations or reference cards to correspond to the changes in circuit connections. The present structural form and arrangement of the designation strip is designed to offer practical advantages over the strip constructions as heretofore made so as to more satisfactorily meet the requirements and conditions of use.

Further advantageous features include the supporting of the individual cards to have a slight longitudinal curvature or flexing so as to reduce light reflecting areas; readily releasable mounting of the designation strip holder upon the jack mounting of panel with a slip-on assembling motion and the supporting of the designation cards to be clearly visible without interfering shadows from its supporting structure.

The aforesaid and other advantages of the present invention will be more fully understood by reference to the accompanying drawings wherein like parts are indicated by corresponding reference numerals in the several views.

In the drawings:

Fig. 1 is a view in front elevation showing the designation strip of the invention as applied to a supporting switch panel.

Fig. 2 is a top plan view thereof.

Fig. 3 is an enlarged vertical sectional view taken on line 3—3 of Fig. 1.

Fig. 4 is a similar view taken on line 4—4 of Fig. 1.

Fig. 5 is a perspective view of the associated designation card and transparent envelope in separated position, and

Fig. 6 is a plan view of the sheet metal blank as stamped out to form the holder or supporting bar.

Included among the features and advantages of the present improvement is a simplified one piece holder or supporting bar adapted to be inexpensively stamped from sheet metal and formed at regular intervals throughout its length with retaining tongues up-turned to provide guide members and stops for the reception of a plurality of separable designation cards; the provision of protective transparent envelopes individual to

2

each of the designation cards to be separable therewith and having provision for interlocking engagement with the supporting bar in a manner facilitating the removal of single cards for replacement while at the same time securely retaining the cards and envelopes against accidental dislodgement.

In the preferred embodiment of the invention as illustrated in the drawing, the features thereof are incorporated in a multiple display card designation strip of the type as employed with telephone switch boards and comprises a supporting strip of suitable length adapted to be positioned horizontally on the panel so as to support the designation or reference cards with relation to the respective jacks or signal lamps. In the arrangement as shown the switch panel is indicated at 1 having horizontally aligned screws 2 threaded thereto for the attachment of the designation strip holder or supporting bar. The holder is stamped from a single piece of sheet metal as illustrated in Fig. 6 and is bent or folded upon itself upon a longitudinal line providing an elongated, channelled body having parallel spaced walls 3 and 4 connected at their upper edges by the return bend 5. It is formed with vertical edge slots 6 formed in the walls 3 for slip-on assembling with the securing screws 2. The other walls 4 are formed with integral, spaced tongue extensions 7 extended from the lower edge of the wall and bent outwardly and upwardly as shown at 8 and 9 thus to form stops and guide members for the reception of designation cards which are shown at 10. Each of the cards is contained within a transparent protective envelope 11 formed of sheet cellulose acetate longitudinally folded on itself as best shown in Fig. 5 providing a channel for the reception of the card 10.

The tongue extensions 7 as shown are spaced at regular intervals and the length of the cards 10 which have the reference characters or indicia printed thereon are of a length slightly less than the distance between the center lines of the tongues and the protective envelopes 11 are co-extensive therewith whereby when inserted from above, as indicated in Figs. 3 and 4, they will have support upon the base of the tongues. The cards are positioned with the bend of the envelope uppermost so as to present an upper rounded surface.

For the securing of the designation device or card assembly, composed of the card 10 and the transparent envelope 11, the outer wall 4 is formed with outwardly pressed shoulder extensions 12—12 united at their upper end by curved por-

tions 13 with the holder wall and presenting downwardly directed retaining shoulders or edges. These shoulders are positioned symmetrically with relation to the retaining tongues 7 and intermediate thereof with a pair associated with each of the designation cards. The protective envelopes 11 are punched to provide apertures 14 in their innermost walls positioned for registration with and to receive therein the shoulders 12 when properly positioned so as to retain the cards or markers against accidental dislodgement. The shoulders or stops 12 in their outward deflection may also be to a degree to establish a slight outward deflection of the card and its associated envelope so as to have a slight longitudinal curvature as indicated in Fig. 2 from which it results that, by reason of the flexing, areas of light reflection from a given point are reduced so as to improve visibility and reduce interferences of that nature. The improved designation strip structure as described supports the reference cards outwardly from the panel in a manner to assure of unshadowed display and with a supporting arrangement devoid of exposed sharp edges of such character as might catch the clothing. In the latter connection, the rounded bend of the envelopes 11 extending above the upper edges of the tongues 7 act as a protection or guard against interference from the latter. As will be appreciated, the structural arrangement provides for an easily performed slide or slip-together assembling of the designation strips as a whole with relation to the panel and also with relation to the replacement of the individual designation cards as may be required. In addition to providing for a slide-on assembling of the holder by means of the slots 6 formed in the inner walls 3 of the holder, the outer wall 4 is also formed with slots 15 in alignment with the slots 6 so as to give access to the securing screws for additional tightening as may be desired. Accordingly with the arrangement of the securing screws as shown, in the final assembly they are covered by an over-lying designation card thereby presenting a more sightly appearance and also discouraging tampering.

While I have shown and described an improved embodiment of the features of the invention, it will be understood that varied modifications may be made therein without departing from the scope of the invention as defined in the appended claims.

What is claimed is:

1. A designation strip of the character described comprising a holder member bent upon itself along a longitudinal line providing a channel section with an inner wall having openings for securing elements and an outer wall having integral tongues spaced at intervals and outwardly and upwardly turned to provide stop and guide supports for separable designation units, said outer wall also having outwardly pressed shoulders to fit into and retain said designation units.

2. A designation strip of the character described comprising a holder bar member bent upon itself along a longitudinal line providing a channel section with an inner wall having lower edge opening slots for securing elements and an outer wall having integral tongues spaced at intervals and outwardly and upwardly turned to provide stop and guide supports for separable designation units, said outer wall also having outwardly pressed shoulders to fit into and retain said designation units.

3. A designation strip assembly of the character described comprising a holder bar member formed of sheet material, and having integral tongues spaced at intervals and outwardly and upwardly turned to provide stop and guide supports for separable designation units, each consisting of a card and cover, said bar member also having outwardly pressed shoulders to register with said covers and thereby retain said designation units.

4. A designation strip assembly of the character described comprising a holder member bent upon itself along a longitudinal line providing a channel section with an inner wall having lower edge opening slots for securing screws and an outer wall having integral tongues spaced at intervals and outwardly and upwardly turned to provide stop and guide supports for separable card members and separable designation card units fitted to the guide supports consisting of a card and an envelope therefor of transparent material and outwardly pressed shoulders integral with said holder to effect interengagement between the envelope and the holder for retaining of the card units.

5. A designation strip assembly of the character described comprising a holder member bent upon itself along a longitudinal line providing a channel section with an inner wall having openings for securing screws and an outer wall having integral tongues spaced at intervals and outwardly and upwardly turned to provide stop and guide supports for separable card assemblies, and separable designation card assemblies fitted to the guide supports consisting of a card and an envelope therefor of transparent material, said envelope having perforations therein and said holder outer wall being formed with outwardly pressed shoulders registering with the perforations for retaining of the card members.

6. A designation strip assembly of the character described comprising a holder member bent upon itself along a longitudinal line providing a channel section with an inner wall having lower edge opening slots for securing screws and an outer wall having integral tongues spaced at intervals and outwardly and upwardly turned to provide stop and guide supports for separable card members, and separable designation card assemblies fitted to the guide supports consisting of a card and a channeled envelope therefor of transparent material folded longitudinally on itself, said envelope having spaced perforations in its rear wall and said holder outer wall being formed with outwardly pressed shoulders registering with the envelope perforations for retaining of the card members.

7. A designation strip assembly of the character described comprising a holder member formed of sheet metal bent upon itself along a longitudinal line providing a channel section with an inner wall having openings for securing screws and an outer wall having integral tongues spaced at intervals and outwardly and upwardly turned to provide stop and guide supports for separable card members, and separable designation card assemblies fitted to the guide supports consisting of a card and an envelope therefor of transparent material, said envelope having perforations therein and said holder outer wall being formed with outwardly pressed shoulders registering with the perforations for retaining of card members and having an outward deflection to a degree to effect a longitudinal flexing of the card.

8. A designation strip assembly comprising a holder member formed of sheet metal bent upon

itself along a longitudinal line providing a channel section having spaced inner and outer walls united by an upwardly positioned return bend and having its inner wall formed with lower edge opening slots for the reception of securing screws and the outer wall having integral tongues on its lower edge spaced at regular intervals and outwardly and upwardly turned to provide stop and guide supports open at the top for the reception of separable card members, and separable designation card assemblies fitted to the guide supports and consisting of a card and an envelope therefor of sheet cellulose acetate folded on a longitudinal line and positioned with its fold uppermost.

9. A designation strip assembly comprising a holder member formed of sheet metal bent upon itself along a longitudinal line providing a channel section having spaced inner and outer walls united by an upwardly positioned return bend and having its inner wall formed with lower edge opening slots for the reception of securing screws and the outer wall having integral tongues on its lower edge spaced at regular intervals and outwardly and upwardly turned to provide stop and guide supports open at the top for the reception of separable card members, and separable designation card assemblies fitted to the guide supports and consisting of a card and an envelope therefor of sheet cellulose acetate folded on a longitudinal line and positioned with its fold uppermost, said envelope being formed with longitudinally spaced apertures adjacent to its ends and said holder member outer wall having outwardly pressed shoulders positioned to register with the apertures.

10. A designation strip assembly comprising a

holder member formed of sheet metal bent upon itself along a longitudinal line providing a channel section having spaced inner and outer walls united by an upwardly positioned return bend and having its inner wall formed with lower edge opening slots for the reception of securing screws and the outer wall having integral tongues on its lower edge spaced at regular intervals and outwardly and upwardly turned to provide stop and guide supports open at the top for the reception of separable card members, and separable designation card assemblies fitted to the guide supports and consisting of a card and an envelope therefor of sheet cellulose acetate folded on a longitudinal line and positioned with its fold uppermost, said envelope having longitudinally aligned apertures in each end portion and said holder member outer wall having outwardly pressed shoulder portions formed with an upwardly positioned curved junction and positioned to register with the apertures.
